UNITED STATES PATENT OFFICE.

ROY RICHARDSON, OF MARTINSBURG, WEST VIRGINIA.

SNOW ERADICATOR.

1,402,091.

Specification of Letters Patent. Patented Jan. 3, 1922.

Application filed January 2, 1919, Serial No. 269,192. Renewed May 5, 1921. Serial No. 467,012.

To all whom it may concern:

Be it known that I, Roy RICHARDSON, a citizen of the United States, resident of Martinsburg, West Virginia, have invented certain new and useful Improvements in Snow Eradicators, of which the following is a specification.

My invention is a snow eradicator for use with locomotives and is designed to melt the snow from the road bed as the locomotive advances along the track.

The invention consists in the features and combination and arrangement of parts hereinafter described and particularly pointed out in the appended claims.

In the accompanying drawings:

Figure 1 is a plan view of the eradicator member by which steam is delivered upon the road bed at the fore part of the locomotive adjacent the pony truck.

Fig. 1^a is a detail sectional view of a header forming part of the eradicator structure.

Fig. 1^b is a side view of the parts shown in Fig. 1^a.

Fig. 2 is a sectional view across the boiler with parts shown in elevation and parts broken away.

Fig. 3 is a side view in the nature of a diagram showing the connection to some of the parts shown in Fig. 2.

Fig. 4 is a detail longitudinal section of the valve mechanism, and

Fig. 5 is a transverse section of the valve of Fig. 4.

In these drawings 1 indicates a grating consisting of a series of steam pipes connected to headers 2 and to this pipe system steam is supplied through the supply pipes 3, 4, so that the steam will be distributed throughout the same to be discharged through the perforations 1^b in the under side thereof, upon the snow or ice on the roadway causing it to melt away rapidly as the engine proceeds at a moderate rate of speed.

The pipes 1 extend across from one header 2 to the other and shorter pipes 1^a are arranged between the wheels of the pony truck and are connected with the supplemental headers 2^a, these supplemental headers receiving steam from certain of the pipes 1

and distributing the steam to the shorter pipes. By this construction spaces *a* and *b* are left for the accommodation of the wheels of the pony truck.

55

The steam distributor or grating is of considerable area as shown in Fig. 1 and as indicated it is supported beneath the fore part of the locomotive by suitable hangers 5 attached to and depending from the pilot board 6 and by other hangers 7 depending from and attached to the saddle frame 8. These hangers are attached at their lower ends to bars 9 which by coupling loops 10 support the pipes 1.

65

As before stated the steam is supplied to the pipe system or grating by the pipes 3, 4, and these extend down from valve boxes 11, 12, within the housings 12^a, extending from the boiler shell to the steam chests 13. These boxes are provided each with a slide valve 14 controlling ports 15 which when open allow steam from the dome to pass through the pipes 16 to the steam chests but when these slide valves are adjusted to cut off the 70 direct communication between the pipes 16 and the steam chest part of the steam supplied by pipe 16 will flow through by-pass pipe 17, 17^a, to the steam chest and part will go through the pipes 3 and 4 to the steam distributor or snow eradicator.

75

The by-pass pipe 17, 17^a, is in the form of an upwardly extending loop having at its upper portion a supplemental throttle valve 18 under the control of the engineer through rod 19. The pipes 3 and 4 are supplied with hand operated valves 19 and 20 by which the engineer can regulate the flow of steam through these pipes to the eradicator grating. The slide valves 14 are of special construction, each having a flange 14^a guided in a suitable channel in the valve box, as at 14^b, and having an upwardly extending boss or reduced portion 14^c which receives a yoke 14^d connected by a rod 21 with a lever 22 which is operated from the engineer's cab by a suitable connection 23. The yoke 14^d fits the boss 14^c of the valve loosely so that the steam pressure in pipe 16 will act to keep the valve seated. The valve casing is 80 made of two parts 11^a and 11^b held together by bolts passing through their flanges.

85

90

95

100

In order to secure a maximum degree of opening with a minimum amount of movement of the slide valve I provide two ports in the valve seat and two ports in the valve, the combined area of which is sufficient to deliver the proper amount of steam from the pipes 16 to the steam chests for the running of the engine. It will be noted that I utilize the pipes 16 extending from the header 16^a as the means for conveying steam both to the steam chests and to the eradicator, this being accomplished by the use of the valve and by-pass interposed in this pipe 16 on its way to the steam chest and the arrangement permits the delivering of the full supply of steam to the steam chest or part to the steam chest and part to the eradicator. No additional piping besides the ordinary piping 16 is required with my attachment and thus the invention is rendered simple in construction and its installation in connection with the ordinary parts of the locomotive is facilitated.

It will be observed that only one by-pass pipe 17, 17^a, is necessary as the steam to the right hand steam chest is supplied from this same by-pass pipe through a transverse pipe 17^b, this pipe connecting with the steam chest at the point 17^c beyond the right hand slide valve.

Both of the slide valves are operated through the same connections 23, 22 for which purpose the lever 22 is connected with a transverse rock shaft 24 mounted in suitable brackets 25 on the frame and having at its right hand end, Fig. 2, an upwardly extending arm shown in dotted lines at 26 to connect with the right hand slide valve.

Having thus described my invention what I claim is:—

1. In combination with a locomotive, an eradicator for snow and the like comprising grating made up of long transverse tubes at its front and rear portion, and short transverse tubes at its intermediate portion, headers with which the long transverse tubes connect and headers with which the short transverse tubes connect, the headers of the short tubes being located closer together than the headers of the long tubes, the said structure providing spaces at the sides of the short headers in which spaces the wheels of the pony truck are located and steam pipe connections leading to the grating, substantially as described.

2. In combination with a locomotive, an eradicator for snow and the like, comprising a steam conducting member to deliver the steam against the snow at the fore part of the locomotive, valve means located in the steam pipe connection leading from the header of the boiler to the engine steam chest whereby a portion of the steam ordinarily supplied to said steam chest will be

diverted to the eradicator, substantially as described.

3. In combination with the boiler and steam chest of a locomotive, a steam pipe connection to convey steam from the boiler to the steam chest, an eradicator for snow and the like, a valve in the said steam pipe connection, a by-pass from the said steam pipe connection to the steam chest, a steam supply pipe extending from the said steam supply connection first mentioned to the eradicator and a valve which when open will allow steam from the header to pass direct to the steam chest and when closed will allow part of the steam to flow through the by-pass to the steam chest and part through the pipe connection to the eradicator, substantially as described.

4. In combination with a steam chest and boiler of a locomotive, a steam supply connection between said parts, a valve in said connection, a by-pass from said steam supply connection to the steam chest, a steam pipe extending from the said steam supply connection to the eradicator, a valve controlling the flow of steam through the steam supply connection and which when closed will cause steam to pass through the by-pass and the pipe connection leading to the eradicator, a branch pipe extending from the by-pass to the opposite steam chest and a valve in the steam supply connection leading from the boiler to the said opposite steam chest, and means for controlling both of said valves, substantially as described.

5. In combination with the steam chests and boiler of a locomotive, a pair of steam supply connections between said parts, a by-pass between one of the steam supply connections and one of the steam chests, a supplemental throttle valve in said by-pass, a branch connection from the by-pass to the opposite steam chest, steam supply pipes from the steam supply connection first mentioned, an eradicator to which steam is delivered by the said steam supply pipes, valves in said steam supply pipes and valves in the steam supply connections first mentioned to cut off the direct flow of steam from the boiler to the steam chests, whereby steam will flow through the by-pass and branch pipe to the steam chests and through the pipe connections to the eradicator, substantially as described.

6. In combination with a locomotive, an eradicator, a steam supply connection from the boiler of the locomotive to the steam chest, a by-pass from said steam supply connection to the steam chest, a steam pipe leading from said steam supply connection to the eradicator, a slide valve in said steam supply connection and a yoke connected with the slide valve for operating the same, said

yoke leaving the slide valve free to be pressed upon its seat by the steam pressure from the boiler, substantially as described.

7. In combination with a locomotive, an 5 eradicator for snow and the like comprising a grating made up of transverse tubes extending to the front and rear of the pony-truck, headers with which the transverse

tubes connect, and a header connecting the front and rear portions of the grating, the 10 said structure providing spaces in which the wheels of the pony-truck are located, and steam pipe connections leading to the grating, substantially as described.

In testimony whereof, I affix my signature. 15
ROY RICHARDSON.
